GAME APPARATUS

Howard R. Doty, Glenside, Pa.

Application May 6, 1935, Serial No. 19,942

6 Claims. (Cl. 273—102)

The principal objects of my invention are to provide a game in which elements appearing visually similar and effectively indistinguishable as regards the portions of their surfaces exposed to view from a given direction may be differently and alternatively set as regards the instant position of one of the said elements instantly identified by its instant condition of relatively greater susceptibility than another of the said elements to displacement; and to provide a game in which a player's success depends upon his displacing an element, the instant location or condition of which relative to another element not equally susceptible to displacement has been selectively and alternately predetermined by an opponent without the said player's specific knowledge.

In the accompanying drawing:

Fig. 1 represents a front view of a disk, 101, containing an opening, 104.

Fig. 2 represents a front view of a block, 102, of such size and shape as to fit into the opening 104.

Fig. 3 represents a front view of a panel, 103, containing a plurality of apertures which are indicated by numbers 106, 107, 108 and 109, respectively.

Fig. 4 represents an edgewise view of panel 103 with disk 101 attached thereto by pivot 110, so that the disk can be turned relative to the panel.

To operate this apparatus, block 102 is placed in opening 104, where it may be retained, if ordinary fitting, friction or gravity, is not sufficient, by a spring. One form of such optional spring is shown as 105 in Fig. 1.

Disk 101, carrying with it block 102, is then turned relative to panel 103, on pivot 110, to an alternatively selected position such that block 102 is in apposition with one of the apertures 106, 107, 108 or 109, so that to a person looking from the opposite side of panel 103 the location of block 102 is not visually determinable, since what such a person would see behind any given aperture might be either block 102 or disk 101, these two elements being visually similar as to character of surface, and no distinguishable identifying differences being exposed to his view.

I prefer to make block 102 and opening 104 a little larger than any of the apertures 106, 107, 108 and 109 in order that other provisions or operative precautions against visibility and recognition of the edges of block 102 and opening 104 may be rendered unnecessary, but this larger size of the block and opening relative to apertures 106, 107, 108 and 109 is not essential.

Specific knowledge, on the part of a person looking at the apparatus from the side of the

panel 103 opposite to that on which the disk 101 and block 102 are located, of the instant selected setting may be avoided by requiring him to avert his gaze while such setting is being made, or by manipulating disk 101 too rapidly for his eyes to follow its movements, or by interposing any physical body between his eyes and the apparatus during such manipulation. These are matters of rule and procedure, the essential requirement to be fulfilled by the apparatus being that, once the manipulative alternative setting has been made, there shall effectively be no readily recognizable distinguishing differences between the portion of block 102 seen through one of the apertures and the portions of disk 101 seen through other apertures, as viewed by a person looking from the side of panel 103 opposite to disk 101 and block 102 and from such distance as may be appropriate to his performance of his function in the game.

After the completion of a manipulative and selective setting as above described, culminating in the alternatively selective setting of disk 101 and block 102 relative to apertures 106, 107, 108 and 109, the person mentioned in the preceding paragraph, whom we shall call player A, attempts to displace block 102 from its position in opening 104. This he may accomplish by directing a suitable impulse against block 102, such as a push with his hand or some implement, or the impact of an object shot or thrown. In any case, he is faced with the problem of guessing or otherwise determining the location of block 102 in order that he may displace it. If when, unknown to him, block 102 is (from his viewpoint) behind aperture 107, he directs his attack against what he sees behind aperture 106, or 108, or 109, he will encounter disk 101 which will not yield or be effectively displaced. If, however, he directs his attack against what he sees behind aperture 107 at such a time, he will encounter block 102 and it will be readily displaced.

If he is allowed only one trial, his success may depend entirely upon guess or chance, in the apparent ratio of one to the number of apertures in panel 103. If, however, he is allowed several trials, his chance ratio will improve through the knowledge gained by each unsuccessful attempt; for instance, if in the above situation he attacks first 108, then 106, then 109, he will have learned by trial, error and elimination that block 102 is behind aperture 107.

The rules for playing the game are susceptible of infinite variation and are not claimed as pat-

enable, but for illustrative purposes typical playing procedure is indicated as follows:

Players may be allowed to use blunt-pointed darts for the purpose of attacking locations where they surmise that they might displace block 102. Let us suppose that when taking his turn at this function of play a player is called the shooter, and is supplied with four such darts, corresponding to the number of possible alternative settings of the disk and block. We shall refer to his instant opponent, who makes a manipulative setting of the apparatus in anticipation of the shooter's play, as the blocker.

The blocker having made his setting, the shooter then proceeds with his attack, being credited with a score for each dart he throws along a path on which the block is located at the commencement of his turn. Thus, supposing he starts by displacing the block with his first shot, and further supposing he throws all his remaining darts through the aperture in panel 103 defining the position of block 102 prior to such displacement, he may score four times at one turn. Or, if he misses with the first dart or by wrong selection hits disk 101 therewith, he cannot thereafter score more than three times at that turn because he has but three darts remaining and has failed to score with the first. Obviously he may also be unsuccessful with the second dart, leaving himself but two further chances; he may fail again and leave himself with but one; he may by bad selection and bad throwing combined fail to displace the block and hence fail to score at all; or he may after displacing the block and so beginning to score, miss the aperture with any succeeding dart and thus fail to add to his score.

When the shooter has completed his turn by throwing all of his darts, and when his score, if any, has been recorded, he may become the blocker and the player who opposed him as blocker may become the shooter for the next turn; or one or the other or each of them may give place to another player for the next turn, it being possible for two or many persons to play by taking turns at the different functions of the game in any mutually satisfactory order or system of rotation.

It is clear that adding to the number of elements comparable with and functionally counterparts of disk 101 or block 102, or either of them, whether or not like those illustrated as to form, would introduce no addition to the principle.

All such optional variations are anticipated and included in this invention as described herein.

It has likewise been made clear that the nature of the impulse utilized in the attempt to dislodge an element is optional and may be pressure with the hand or any implement, or impact of any object shot or thrown, rolled, slid or thrust forward, or any mechanical or electrical or other application of energy, all being effective equivalents.

I claim:

1. In a game device, including, at least: two members operatively associated and arranged for adjustment relatively to each other; one of said members having a displaceable and replaceable

target element and a surface portion identical in appearance to a surface portion of said element; the other member having a plurality of openings making portions of said target element and first member visible therethrough, and means to conceal the position of the aforesaid target element.

2. In a game, including, at least: two members operatively associated and arranged for adjustment relatively to each other; the first of said members having a displaceable and replaceable associated element and at least one surface portion identical in appearance to a surface portion of said element, the said surface portions being arranged for exposure to attack in alternative positions relative to the second of said members; the second member comprising a plurality of openings making said surface portions visible therethrough; and means to conceal the respective positions of said first member and its associated element.

3. In a game, including, at least: a plurality of target elements and a body member; said target elements having surface portions identical in appearance, and being operatively associated and arranged for adjustment relatively to said body member, and at least one but not all of them being effectively displaceable and replaceable as regards its operative association in an adjustment effectuated relatively to said body member; said body member comprising a plurality of openings making portions of said target elements visible therethrough; and means to conceal the relative positions of the said target elements.

4. In a game device, including, at least: a plurality of target elements and a member relatively to which the said elements may be alternatively adjusted; the said target elements having surface portions identical in appearance, at least one of said elements being effectively displaceable and at least one of said elements being effectively fixed as against displacement from an adjustment effectuated relatively to the said member; and means to conceal the relative positions of a displaceable element and a fixed element.

5. In a game device, including, at least: a member comprising a plurality of defined spaces; and an assembly of target elements susceptible of adjustment relatively to the said member in such manner as to result in there being in conjunction with an alternatively selected defined space, a target element effectively fixed as against displacement, and in conjunction with another alternatively selected defined space, at the same time, an effectively displaceable target element; and means to conceal the relative positions of said target elements.

6. In a game device, including, at least: a member comprising a plurality of defined spaces; and an assembly comprising a plurality of target elements related to the said defined spaces and adjustable in such manner that there may be, in alternative arrangements, a displaceable element related to one defined space while there may be a fixed element related to another defined space; and means to conceal the relative positions of displaceable and fixed elements.
